UNITED STATES PATENT OFFICE

151,873

DESIGN FOR A DOOR KNOCKER

Herbert Cohn, Baltimore, Md.

Application March 26, 1946, Serial No. 127,952

Term of patent 14 years

(Cl. D10—7)

To all whom it may concern:

Be it known that I, Herbert Cohn, a citizen of the United States of America, residing at Baltimore, in the State of Maryland, have invented a new, original, and ornamental Design for Door Knockers, of which the following is a specification, reference being had to the accompanying drawing, forming a part thereof, and wherein the figure is a front elevational view, in perspective, of a door knocker showing my new design.

I claim:

The ornamental design for a door knocker, substantially as shown.

HERBERT COHN.
